PROCESS OF COHERENTLY UNITING PLASTIC MATERIAL TO SHEET METAL

James S. Reid, Shaker Heights, Ohio, assignor to
The Standard Products Company, Cleveland,
Ohio, a corporation of Ohio

Application January 16, 1936, Serial No. 59,365

6 Claims. (Cl. 91—70)

This invention relates to a process of coating metal with a plastic composition, the general object of the present invention being the provision of a simple and improved process of coating metal, such as a strip of steel, with a plastic composition, such as a layer of rubber, the rubber being coherently united to the steel.

As will hereinafter more fully appear, the present improved process involves the heating of the metal to be coated in a chamber which is being continuously evacuated, with the consequent removal of air, moisture and the like from at least the surface spaces or crevices of the metal. The heated metal is then passed into an evacuated cooling chamber, with consequent cooling and contraction of the metal. The chilled and contracted metal is then passed into contact with the hot plastic material, with consequent coating, coherently, of the metal with such plastic material. If rubber is the plastic material coherently united to the metal, such rubber-coated metal may be subjected next to a suitable vulcanization operation to properly cure the rubber.

The nature of the present improved process will be more clearly understood from the following description of such process and of certain apparatus by the use of which it may be practiced. It is to be understood, however, that such apparatus is illustrative only.

In the accompanying drawing, to which reference will hereinafter be made, Fig. 1 is a side view, partly in elevation and partly in vertical section, of simple apparatus for practicing the present improved process, such apparatus being more or less diagrammatically illustrated; Fig. 2 is a plan view of such apparatus; and Fig. 3 is an exaggerated cross-sectional view of a strip of steel showing its expansion and contraction during the different stages of the present process.

Referring to the drawing, a comparatively thin sheet of metal, such as a thin strip of steel 1, is drawn from a supply reel 2 over a guide pulley 3 suitably mounted on a substantially closed cleaning tank 4. In said tank is a suitable cleaning agent 5 for said metal strip, one such agent being a dilute solution of a mineral acid, such as an aqueous solution of hydrochloric or sulphuric acid. The cleaning solution is preferably heated by any suitable heating means, such as by a gas burner 6, and the vapors rising from the cleaning solution exert a cleaning action upon the steel strip in its travel through the tank 4, said strip passing from the guide pulley 3 down around a guide pulley 7 and thence upwardly at an angle

over a guide pulley 7', the guide pulleys 7 and 7' being suitably mounted on the tank 4.

The vapors of the cleaning solution condense in the cleaning tank 4 and the major part of the condensate, together with any dirt or grease removed from the metal strip, fall into a compartment 8 of the tank 4, from the bottom of which compartment the dirt, etc., may be periodically removed. A partition 8a of said tank, by means of which the compartment 8 is formed, is of such height that the condensate collecting in the compartment 8 overflows said partition at sufficiently frequent intervals to maintain enough of the cleaning solution in the main part of the tank 4 to provide the necessary amount of vapors for proper cleaning of the metal strip.

From this cleaning unit, the steel strip next passes to a suitable heating unit 9 here shown as supported on legs 9a and having a sealed heating chamber 9c continuously evacuated by means of a suitable vacuum pump 10. As the steel strip is conveyed through this heating chamber 9c, it is heated by any suitable means, such as by radiation from a suitable electric resistor 9b connected by wires L1, L2 to any suitable source of current.

As shown, the entrance opening of the heating chamber 9c is, of course, suitably sealed, as at 11, in order that the proper degree of evacuation in the heating chamber may be attained. During its passage through the evacuated heating chamber 9c, the steel strip expands in cross-section, as indicated at A, Fig. 3, the original cross-sectional size of the strip being indicated at B.

The heating of the steel strip and the evacuation of the heating chamber 9c through which the strip passes serve to remove any moisture or vapors present upon the surface of the metal. The expansion of the metal and the evacuation of the heating chamber also serve to effect the removal of gases from the spaces or minute crevices between the crystalline structure of the metal and may even effect the removal of some of the gases combined with or occluded in the metal. It is to be understood, however, that the present invention is not limited to any particular degree of heating of the metal strip, although it may be stated that the temperature to which it is heated is substantially above normal room temperature but does not exceed the point which will produce an atomic rearrangement of the metal. In other words, if the metal of the strip is steel, it should not be heated above the recalescence point.

From the chamber 9c of the heating unit, the metal strip is drawn through a suitable conduit

12 into a suitable cooling unit 13 in which the metal strip is cooled sufficiently to effect contraction thereof, as indicated at C, Fig. 3. Because of cooling fins 12a with which said conduit is externally provided, the metal strip receives some preliminary cooling before it enters a guide tube 17 of the cooling unit, said guide tube being surrounded by the cooling chamber 13a of a cooling tube 14 with which the guide tube is coextensive and of which it may be an integral part, as shown. Through the cooling tube chamber 13a is circulated a suitable refrigerant from a refrigerating device 15, suitably connected to said cooling chamber by supply and return pipes 16. Inasmuch as the guide tube 17 communicates with the conduit 12 which in turn communicates with the heating chamber 9c, said guide tube and said conduit are maintained, like said heating chamber, in an evacuated condition by operation of the vacuum pump 10. The cooling fluid or refrigerant circulated through the cooling chamber 13a is of such a nature that the metal strip, as it passes through the guide tube 17 surrounded by such cooling chamber, is maintained substantially below normal temperatures, preferably close to or below 0° C., to effect the desired contraction of such metal strip, as will be readily understood.

From the cooling unit, the cooled and contracted metal strip is drawn into an extruding unit 20, within the chamber 21 of which is a hollow cone-shaped element 22 into which project forward ends of the cooling tube 14 and the guide tube 17 therewithin. The apex of the cone-shaped element 22 terminates adjacent the discharge die member 23 of the extruding unit and is provided with a suitable exit slot for the metal strip 1, said exit slot being in alignment with the discharge opening of the die member 23, as shown.

The plastic material, such as rubber, which is to be coherently united with the metal strip 1, enters the extruding chamber 21 through a conduit 21a connected to a suitable hopper 24, the plastic material being forced through said conduit from said hopper into said chamber by means of a worm 25 arranged within said conduit and driven by the rotation of a pulley 26 associated therewith and operatively connected to any suitable source of power.

The cooled and contracted metal strip contacts the hot rubber or other plastic material upon emerging from the cone-shaped projection 22 within the extruding chamber 21, and the effect of such contact is the sudden expansion of the metal strip, the consequent sudden opening up of the spaces and crevices thereof, and the resulting uniting, coherently, of the rubber or other plastic material with the metal strip. The coherent uniting of the plastic material and the metal is believed to be due, in part, to the vacuum effect which is produced in each of the minute spaces or crevices of the metal by the sudden expansion of the crystals thereof in the presence of the heated plastic material, the effect being to draw the plastic material by suction into such spaces or crevices. It is to be understood, however, that the present invention is not to be limited by the aforesaid belief concerning the coherent character of the uniting of the plastic material to the metal strip, as such coherent results may be due wholly or in part to other causes.

It is to be noted that the metal strip is subjected to the evacuating effect of the vacuum

pump 10 until it emerges into the extruding chamber 21 and that the cooling effect of the refrigerant is also maintained until such emergence occurs. Although the operation of the worm 25 effects a heating of the plastic material before it reaches the extruding chamber, additional heating means for such plastic material may be utilized, if necessary or desirable.

After the plastic-coated metal strip is drawn from the extruding unit, it is permitted to cool to normal temperatures, although it may be subjected to other treatment, if desired. For instance, if the plastic material is raw rubber, the coated metal strip is subjected to a vulcanization operation to cure the rubber, as will be readily understood.

Although the present invention is particularly applicable to the coating of steel sheets or strips with rubber, it is to be understood that said invention is not limited thereto, as any suitable plastic material or composition may be used for such coating purposes, such as gutta-percha, ozo-kerite, asphalt or other bituminous material. It is also to be understood that if the surface of the metal is free of impurities, such as grease and dirt, the cleaning step may be omitted.

To those skilled in the art, many modifications and widely different embodiments and applications of the invention will suggest themselves, without departing from the spirit and scope of this invention, the present disclosure being merely illustrative.

What I claim is:

1. The process of coherently uniting hot plastic composition to metal, which comprises heating the metal, with consequent expansion thereof, subjecting the heated metal to a vacuum effect while it is in such expanded condition, with consequent removal of air, moisture, etc., from the spaces or crevices of the metal, cooling the expanded metal while it is still being subjected to a vacuum effect, with consequent contraction of said metal, and applying to the contracted metal the hot plastic composition without exposing the metal to the atmosphere, with consequent coherent uniting of said plastic composition to said metal.

2. The process of coherently uniting a hot plastic composition to metal, which comprises heating the metal in an evacuated chamber, with consequent expansion of the metal and the removal of air, moisture, etc., from the spaces or crevices thereof, cooling the heated metal in an evacuated chamber, with consequent contraction of the metal, and applying to the cooled metal the hot plastic composition without exposing the metal to the atmosphere, with consequent coherent uniting of said plastic composition to said metal.

3. The process of coherently uniting hot plastic rubber to metal, which comprises heating the metal, with consequent expansion thereof, subjecting such heated metal to a vacuum effect, with consequent removal of air, moisture, etc., from the spaces or crevices of the metal, cooling the expanded metal while it is still being subjected to a vacuum effect, with consequent contraction of the metal, applying hot plastic rubber to said cooled and contracted metal, with consequent coherent uniting of said rubber to said metal, and subjecting the rubber coherently united to said metal to a vulcanizing operation.

4. The process of coherently uniting hot plastic composition to metal which comprises heating the metal in a chamber to expand it, evacuating the chamber to remove air, moisture, etc., from

the surface and spaces or crevices of the metal, cooling the metal to a temperature substantially below normal room temperature to effect a contraction of the metal, and then applying a hot plastic composition to the cooled contracted metal without exposing it to the atmosphere, thereby causing a coherent uniting of the plastic composition to said metal.

5. The process of coherently uniting a hot plastic composition to a ferrous metal which comprises heating the metal in a chamber to a temperature below the recalescence point to expand it while evacuating the chamber to remove air, moisture, etc. from the surface of the metal and 10 from the pores or crevices between the crystalline structure, cooling the metal to a temperature substantially below normal room temperature to effect a contraction of the metal while maintaining a vacuum around the metal, and then applying

ing a hot plastic composition to the cooled contracted metal without exposing the metal to the atmosphere, thereby causing a coherent uniting of the plastic composition to the metal surface.

6. The process of coherently uniting a hot plastic composition to a metal which comprises continuously passing a strip of metal through a heated chamber while evacuating the chamber to expand the metal and remove moisture and gases from the surface and between the pores or crevices of the metal, passing the metal through a communicating evacuated chamber and cooling the metal to a temperature substantially below room temperature to contract the metal, and then passing the cooled contracted metal through a hot plastic composition to expand the metal and cause the hot plastic composition to become coherently united to the metal surface.

JAMES S. REID.
